DESIGN FOR A COMBINED SEAT AND BACK REST FOR A CHAIR OR THE LIKE

Glenn D. Wood, Elkhart, Ind., assignor to Posture Research Corporation, Elkhart, Ind., a corporation of Indiana

Application July 7, 1942, Serial No. 107,443

Term of patent 14 years

To all whom it may concern:

Be it known that I, Glenn D. Wood, a citizen of the United States and a resident of Elkhart, county of Elkhart, and State of Indiana, have invented a new, original, and ornamental Design for a Combined Seat and Back Rest for a Chair or the like, of which the following is a specification, reference being had to the accompanying drawing, forming a part thereof, in which: Fig. 1 is a front perspective view of a combined seat and back rest for a chair or the like, showing my new design. Fig. 2 is a side elevational view thereof.

I claim:

The ornamental design for a combined seat and back rest for a chair or the like, substantially as shown.

GLENN D. WOOD.
